[57] CLAIM

The ornamental design for a hand-held nut gathering tool, as shown and described.

DESCRIPTION

FIG. 1 is a side elevational view of a hand-held nut gathering tool showing my new design, the opposite side being a mirror image of that shown;

FIG. 2 is a rear elevational view thereof;

FIG. 3 is a bottom and side perspective view thereof;

FIG. 4 is a bottom and rear perspective view thereof;

FIG. 5 is a top plan view thereof; and

FIG. 6 is a bottom plan view thereof.

The handle portion is shown broken-away to indicate indeterminate length.

FIG. 1

FIG. 2

FIG. 3

FIG. 4

FIG. 6
